Attorney

UNITED STATES PATENT OFFICE.

EMIL HAVRILLA, OF HOMESTEAD, PENNSYLVANIA.

TOOTHBRUSH.

Application filed September 18, 1924. Serial No. 738,475.

The present invention appertains to a tooth brush and the primary object thereof is to provide a brush of this nature which may be readily adjusted so as to conform to 5 the contour of the dental surface being cleaned.

Another important object of the invention is to provide a means for holding the brush in different adjusted positions.

10 Another very important object of the invention is to provide a brush having a plurality of bristles and means whereby some of the bristles may be adjusted to vary their effective length.

15 Another important object of the invention is to provide a tooth brush of this nature which due to its simple design and few parts may be economically constructed and at the same time capable of operating in a simple 20 manner with efficiency.

Another object of the invention is to provide a device of this nature having an easy 25 operation, one which is durable, reliable, and well adapted to the purpose for which it is designed.

With the above and numerous other objects in view as will appear as the description proceeds, the invention resides in certain novel features of construction, and in 30 the combination and arrangement of parts as will be hereinafter more fully described and claimed.

In the drawing:

35 Figure 1 is a longitudinal section through a brush embodying the features of my invention,

Figure 2 is a top plan view thereof,

Figure 3 is a transverse section therethrough, and

40 Figure 4 is a longitudinal section therethrough showing the brush adjusted in a different position.

Referring to the drawing in detail it will be seen that 10 designates a handle having 45 the brush back 11 extended from one end thereof. A plurality of bristles 12 project from the back 11 and the end thereof is provided with a plurality of slots or openings 13. The rear surface of the back 11 is provided with a groove 14 of dovetail formation 50 to receive an auxiliary back 15 shaped dovetail to slide freely in the groove 14. A plurality of bristles 16 project from the end of the auxiliary back 15 and penetrates in slots 13. The effective length of these 55 bristles 16, therefore, may be changed by

sliding the auxiliary back 15 as will be evident from an inspection of Figures 1 and 4. Thus the contours of the bristles of the tooth brush may be varied to simulate very 60 closely the contour of the dental surface being cleaned.

A handle 17 extends from the auxiliary back 15 alongside of the handle 10. The handle 10 is provided with a plurality of notches 18 for receiving a projection 19 on the handle 17 so that the auxiliary back 15 may be held in different adjusted positions in relation to the back 10. It is preferable to form the handle 17 of some bendable material in order that the end thereof may be moved to disengage the projection 19 from the notches 18 and it is still more preferable that this handle be formed of resilient material in order that it may normally retain the 70 projection in one of the notches. A transverse extension 20 is provided adjacent the end of handle 17 so as to project beyond a side edge of the handle 10 in order that the end of handle 17 may be engaged by a finger 75 and raised to disengage its projection 19 from one of the notches 18.

It is thought that the construction and operation of the brush should now be clearly 85 understood without a more detailed description thereof. It will be apparent from the foregoing that I have devised a novel construction of a toothbrush, which will be cheaply manufactured and will be durable 90 and effective under all conditions and which is not liable to readily get out of order.

It will now be apparent that I have devised a novel and useful construction of a tooth brush, which embodies the features of 95 advantages enumerated as desirable in the statement of the invention and the foregoing description, and while I have, in the present instance shown and described a preferred embodiment of which will give in practice 100 satisfactory and reliable results, it is to be understood that the same is susceptible of modifications in various particulars without departing from the spirit or scope of the invention as hereinafter claimed or sacrificing any of its advantages.

Having thus described my invention, what I claim as new is:

1. A tooth brush of the class described including a back having bristles and an opening therethrough adjacent said bristles, an auxiliary back slidably mounted on the first mentioned back and provided with bristles 110

- extending through the opening whereby the auxiliary back may be moved on the first mentioned back varying the effective length of the bristles extending from the auxiliary back.
2. A brush of the class described including a back, bristles extending from the back, said back being provided with a slot adjacent said bristles, and grooves on the opposite side from said bristles, an auxiliary back slidably mounted in the groove of the first mentioned back, bristles extending from the auxiliary back through the slot, a handle extending from the first mentioned back, a handle extending from the auxiliary back alongside of the first mentioned handle and provided with a projection, said first mentioned handle provided with a plurality of notches for receiving the projection.
- 10
- 15

3. A brush of the class described including a back, bristles extending from the back, said back being provided with a slot adjacent said bristles, and grooves on the opposite side from said bristles, an auxiliary back slidably mounted in the groove of the first mentioned back, bristles extending from the auxiliary back through the slot, a handle extending from the first mentioned back, a handle extending from the auxiliary back alongside of the first mentioned handle and provided with a projection, said first mentioned handle provided with a plurality of notches for receiving the projection, an extension formed on the second mentioned handle and disposed to terminate beyond one side edge of the first mentioned handle.

In testimony whereof I affix my signature.
EMIL HAVRILLA.
